United States Patent Office

Des. 189,284
Patented Nov. 15, 1960

189,284

FAUCET HANDLE

Stephen A. Young, Monticello, Ind. (Flora, Ind.)

Filed Oct. 17, 1958, Ser. No. 53,015

Term of patent 14 years

(Cl. D91—3)

Fig. 1

Fig. 2

Fig. 3

Fig. 4

Fig. 5

I claim:

The ornamental design for a faucet handle, substantially as shown.
